United States Patent Office.

HIRAM LUCAS, OF ROWSBURG, OHIO.

Letters Patent No. 80,981, dated August 11, 1868.

IMPROVED APPARATUS FOR TANNING LEATHER.

The Schedule referred to in these Letters Patent and making part of the same.

TO ALL WHOM IT MAY CONCERN:

Be it known that I, HIRAM LUCAS, of Rowsburg, in the county of Ashland, and State of Ohio, have invented certain new and useful Improvements in an Apparatus for Tanning Leather; and I do hereby declare that the following is a full and complete description of the same, reference being had to the accompanying drawings, making part of this specification, in which—

Figure 1 is a side view of the apparatus.

Figure 2, an end view.

Figure 3, a top view.

Like letters of reference refer to like parts in the different views.

In fig. 1, A represents a tan-vat, of the ordinary structure and size. B is an oblong square frame, fitted to the inside of the vat, and, when therein, one end is supported by the legs indicated by the dotted lines C, fig. 2, whereas the opposite end is supported by the cleats D. Said frame, when in the vat, is indicated by the dotted lines B C, fig. 1.

The frame just described is for the purpose of supporting the hides in the vat, and which are hung transversely in the frame on rods, as indicated by the dotted lines E, fig. 1. Said rods and hides are shown in fig. 3, in which a are the rods and E the hides.

It will be observed by this device that the hides hang vertically in the vat, and close to each other, whereas, in the ordinary way of placing them in the vat, they are laid flat or horizontal, superimposed one above the other, until the vat is full. In this way of arranging the hides, it is necessary, when required to move them, to take each, one at a time, from the vat, and hang them upon poles to drip and dry, or for the purpose of removing the ooze.

This matter of removing the hides is a work of great labor, and attended with great inconvenience and exposure to the wet, thereby adding largely to the expense of the tanned hides, but, by arranging or hanging them upon the frame in the manner above described, the whole number of hides can be taken from the vat at once, by means of the windlass G, said windlass being placed upon the edge of the vat at one end, as shown in fig. 1. The rope or belt H is then made fast to the end of the frame. Now, on winding up the rope, the end of the frame will be elevated from the vat, as shown in fig. 1; the opposite end being provided with side lugs or gudgeons, b, fig. 3, which, as the frame is being raised, rest in the lower notches, c, cut in the edge of a cleat, secured to each inner side of the vat, as indicated by the dotted lines I, fig. 1, and on which the frame turns as it is being lifted. The hides, when the frame is thus lifted in the vat, rest upon the cross-rails, extending from one leg of the frame to the other, as indicated by the dotted lines c, fig. 2.

In this way the hides can be raised entirely from the ooze without being removed from the vat, or the frame may be drawn up so as to lodge the gudgeons in the upper notch c', in which position the frame may be further elevated and the hides lifted out of the vat, as shown in fig. 1, in which position they will soon drip and dry, in consequence of their oblique inclination. It will be obvious that the hides in this position will dry without being hung up for that purpose, hence there will be a large saving of time and labor.

By this means the hides can be handled with much less time for the purpose of removing the liquor, as all that is necessary is to lift one end of the frame, thereby lifting the hides wholly or partially from the vat, so as to give access to the same for the introduction of the pump, for exhausting the spent ooze and removing the tan, which, when replaced by new, the hides are again lowered into the vat as before, with but little labor and expenditure of time.

Hides, by being thus hung in the vat, are more directly in contact with the ooze, hence the process of saturation is more rapid than if they lay superimposed upon each other in the ordinary way, for in this condition, their closeness and pressure upon each other, excludes a free access of the liquor in and about them.

What I claim as my improvement, and desire to secure by Letters Patent, is—

The adjustable rack-frame B and cleats or bearings I, upon which the frame is pivoted when in operation, in combination with the vat, the said frame being raised or lowered with its load of skins by means of the windlass, substantially as and for the purpose set forth.

HIRAM LUCAS.
